UNITED STATES PATENT OFFICE.

DUNCAN MONROE BAILEY, OF FALL RIVER, MASSACHUSETTS, ASSIGNOR TO DRAPER CORPORATION, OF HOPEDALE, MASSACHUSETTS, A CORPORATION OF MAINE.

TIP SUPPORT FOR FILLING REPLENISHING LOOMS.

Application filed June 4, 1924. Serial No. 717,850.

To all whom it may concern:

Be it known that I, DUNCAN M. BAILEY, a citizen of the United States, residing at Fall River, in the county of Bristol and 5 State of Massachusetts, have invented an Improvement in Tip Supports for Filling Replenishing Looms, of which the following description, in connection with the accompanying drawings, is a specification, like 10 characters on the drawings representing like parts.

This invention relates to tip supports for filling replenishing looms whereby the tip end portions of the filling carriers are supported and guided into the shuttle chamber during the transferring operation.

In filling replenishing looms of the type wherein a fresh supply of filling is transferred from the hopper to the shuttle, the 20 base of the filling carrier is engaged by the transerrer while a part of the filling carrier towards the tip is engaged by an arm laterally extended from the transerrer. Looms of this type are usually provided 25 with means to support and guide the tip of the filling carrier as it is transferred to the shuttle, and such tip support is yieldingly held in normal position and gives or yields under the downward pressure of the filling 30 carrier as it is transferred.

It is well known that filling carriers vary in size; that is, the diameter of the filling carrier near the tip portion thereof will vary in different sets, so that while the tip 35 support may properly cooperate with one size of filling carrier to support and guide the tip end portion into its final position in the shuttle chamber, it will not so support and guide a filling carrier of different size 40 or diameter.

One of the objects of the present invention, therefore, is to provide a tip support in a filling replenishing loom, such that filling carriers or bobbins of different sizes or 45 diameters may have their tip portions supported and guided into proper position in the shuttle chamber before passing out of the control of the tip support. In accordance with this general feature of the present 50 invention the tip support is mounted on a fixed element in the machine for pivotal movement thereon, and the amplitude of such pivotal movement as well as the position about which such movement takes place 55 are changeable in accordance with the

character and size or diameter of the filling carriers in use, to the end that any of such filling carriers may have their tip portions supported and guided by the tip support into the final position the filling carrier is 60 to assume in the shuttle.

The various features and new combination of parts will best be made clear from the following description and the accompanying drawings of a good practical form of 65 the invention.

In the drawings:

Fig. 1 is a side elevation of a portion of a filling replenishing loom showing more particularly the transferring mechanism and 70 the present invention associated therewith;

Fig. 2 is an enlarged detached detail showing the transerrer and tip support with the associated parts;

Fig. 3 is a side elevation showing the tip 75 support adjusted and regulated for the support and guidance of filling carriers of a different size than those indicated in Figs. 1 and 2; and

Fig. 4 is a slightly modified form of means 80 for regulating the initial position of the tip support.

Referring to Fig. 1 of the drawings, the filling carriers are shown as mounted in a rotating feeder or hopper to successively 85 move the filling carriers to transferring position after a replenishing operation, but the present invention is not necessarily restricted to this particular type of hopper.

As shown, the loom frame 1 has mounted 90 thereon the hopper stand 2 in which is mounted for rotative movement the hopper 3. The hopper 3 is mounted for rotative movement about the axis 4 and is given a rotative or step movement to present a filling 95 carrier to position for transfer after each replenishing operation. The means for effecting this movement of the hopper 3 forms no essential part of the present invention and may be of any usual character which, being well understood by those familiar with machines of this type, need not be here described.

The filling carriers 5 are mounted in the hopper 3 and are transferred from the hopper to the shuttle by a transerrer 6 which is pivotally mounted on a stud 7 mounted upon the machine frame. Extending downwardly from the hub portion of the transerrer 6 is the arm 8 to which is pivotally 100 105 110

connected at 9 the dog 10 which is adapted to be engaged by the bunter 11 on the lay 12 as the latter moves frontwardly when the replenishing operation is to be effected. The 5 dog 10 may be under the control of a train of mechanism which indicates the condition of the filling in the shuttle, but as such mechanism forms no part of the present invention it is not herein shown and described.

10 The transfferer 6 has extending laterally therefrom the arm 13, as more clearly indicated in Fig. 2, and such arm is provided with the down-turned portion 14 for engaging the outer or tip end portion of the 15 filling carrier or bobbin 5 during the transferring operation. As the transfferer 6 is caused to descend to effect the transfer, the head end portion 15 thereof engages the head portion of the filling carrier or bobbin 20 and the down-turned end 14 of the arm 13 engages the tip portion of the bobbin whereby the bobbin or filling carrier is removed from the hopper and placed in the chamber of the shuttle 16 when the latter is in position 25, as indicated in Fig. 1, that is, when the shuttle is in the filling replenishing box and the lay is about its front center when filling replenishment is to be effected.

Secured in fixed position to the stud or 30 dead shaft 7 is a member or arm 17 on which is pivotally mounted the tip support 18. The tip support 18 is preferably formed as shown and has an end portion 19 which, when the tip support is tilted downwardly 35 into dotted line position, Figs. 1 and 3, extends well into the shuttle chamber without engaging the side of the shuttle itself.

The fixed member or arm 17 has a hub portion 20 through which extends the small 40 shaft or pivotal support 21 having the tip support 18 secured thereto. The pivotal support or shaft 21 extends through the hub 20 and on the inner side thereof carries a sleeve or housing 22. Within the 45 housing 22 and preferably surrounding the shaft 21 is a spring 23, one end of which is secured to the housing at 24 and the other end of which is secured to the hub 20, the tension of the spring being such as to normally tend to turn the tip support 18 in a 50 contra clockwise direction, viewing the present drawing. By providing the housing with a series of openings 25 for the reception of the cotter pin 26, which also passes 55 through the shaft 21, the tension of the spring 23 may be varied.

Extending from the fixed arm 17 is a lug 27 through which extends the regulating or 60 adjusting screw 28 which may be locked in its adjusting position by a set nut 29, and extending above the end of the adjusting screw 28 is the toe 30 of the tip support, the construction being such that under the action of the spring 23 the tip support will be 65 held normally in position with the toe or

stop 30 in engagement with the end of the regulating or adjusting screw 28.

The fixed member or arm 17 as above stated is mounted on the stud or dead shaft 7 and is connected to said stud or dead shaft in adjusted position by a set screw 31 so that when the parts are arranged or regulated for filling carriers of a size such as that indicated in Figs. 1 and 2, the tip support will be turned downwardly from its full to its dotted line position, Fig. 1, during the transfer, and will support and guide the tip of the filling carrier from the hopper to its final position in the shuttle chamber, at which time; that is, when the filling carrier has reached its final position in the shuttle chamber, the end of the tip support will pass from engagement with the tip end of the filling carrier and return to its normal position as indicated in Fig. 1.

It will be noted that the arc or amplitude of movement of the tip support 18 when adjusted for bobbins of a size corresponding to that shown in Figs. 1 and 2, will be such as to maintain the tip support in engagement with the tip of the filling carrier or bobbin from the time it leaves the hopper until it is finally positioned in the shuttle. When, however, bobbins or filling carriers of a different size or diameter than those indicated in Figs. 1 and 2 are employed, the arc or amplitude of movement of the tip support and guide will not be suitable. That is to say, if the bobbins or filling carriers are of a smaller diameter, as indicated in Fig. 3, the arc or amplitude of movement of the tip support will be such as to release the smaller filling carrier or bobbin during transfer before such filling carrier or bobbin reaches its proper or final position in the shuttle chamber. Therefore, the present invention contemplates means for regulating the arc or amplitude of the pivotal movement of the tip support and a change in the position of the center about which the tip support turns, in order to accommodate bobbins or filling carriers of different sizes or diameters.

If it be assumed, for instance, that the tip support has been employed in connection with bobbins or filling carriers such as represented at 5 in Figs. 1 and 2, and is to be employed in connection with filling carriers or bobbins such as 32, Fig. 3, of a different or smaller size or diameter, the machine attendant will adjust the arc or amplitude of movement of the tip support 18 by changing the initial position of the tip support, so that it will be close to or in engagement with the tip end of the filling carrier or bobbin, as indicated in Fig. 3, and will simultaneously therewith manipulate the adjusting screw 31 to alter the position of the axial center about which the tip support turns, from its normal position, as indicated on the line

a—b to the secondary position indicated by the line *a—c*, so that in adapting the tip support for the functional discharge of its purpose in supporting and directing filling carriers of different sizes into their final and proper position in the shuttle chamber, the amplitude of movement of the tip support will be changed, and likewise it may be desirable to change the position of the center 10 about which the tip support turns, so that regardless of the size of the filling carriers or bobbins employed, the tip support may be regulated to properly support and guide filling carriers to their final position in the 15 shuttle chamber.

The amplitude of movement of the tip support will be adjusted by the regulating device or set screw 28, whereas, the position of the center of the tip support will be regulated by the arm 17 and the set screw 31.

In Fig. 4 a slightly modified form of an adjusting device for the amplitude or arc of movement of the tip support is shown, wherein, instead of employing the set screw 28, the arm 17 has mounted thereon a shaft 33, Fig. 4, on which is secured or formed an eccentric 34 which underlies the toe end 30 of the tip support 18. The end of the shaft 33 may be screw threaded and have mounted thereon the set nut 35, whereby upon loosening the nut 35, the shaft 33 may be located more or less to position the eccentric 34 as desired under the toe 30 of the tip support, thereby varying its arc or amplitude 35 of movement.

What is claimed is:

1. In a filling replenishing loom, the combination of a hopper for filling carriers, a transerrer to transfer a filling carrier from the hopper to the shuttle, a yieldingly controlled tip support to guide the tip portion of a filling carrier from the hopper to the shuttle, a fixed member on which the tip

support is pivotally mounted, an adjustable stop for changing the initial position of the tip engaging portion of the support in accordance with the size of the filling carrier to be transferred, and means for adjusting the fixed member to change the center of movement of the tip support during transfer. 45 50

2. In a filling replenishing loom, the combination of a hopper for filling carriers, a transerrer to transfer a filling carrier to the shuttle, a tip support, a fixed member on which the tip support is pivotally mounted, means for varying the amplitude of pivotal movement of the tip support in accordance with the size of the filling carrier to be transferred, and means for varying the position of the pivotal center of the tip support that the tip portions of filling carriers of different sizes may be engaged and guided by the tip support from the hopper to their final position in the shuttle and then pass 60 65 out of engagement with the tip support.

3. In a filling replenishing loom, the combination of a hopper for filling carriers, a transerrer to transfer a filling carrier to the shuttle, a tip support having the free end 70 thereof downturned to enter and guide the tip of a filling carrier into the shuttle chamber, a fixed member on which the tip support is pivotally mounted, means for varying the amplitude of movement of the tip support 75 on said fixed member to accord with the size of the filling carrier to be transferred, and means for varying the position of the pivotal center of the tip support that it may be engaged with the tip portion of filling carriers 80 85 of different sizes from the time they leave the hopper until they reach their final position in the shuttle.

In testimony whereof, I have signed my name to this specification.

DUNCAN MONROE BAILEY.
